UNITED STATES PATENT OFFICE.

ANDREW HUNTER AND CHARLES E. WHITMORE, OF QUINCY, ILLINOIS.

IMPROVEMENT IN MIDDLENS-PURIFIERS.

Specification forming part of Letters Patent No. 150,322, dated April 28, 1874; application filed October 10, 1873.

CASE A.

To all whom it may concern:

Be it known that we, ANDREW HUNTER and CHARLES EDWARD WHITMORE, of Quincy, county of Adams, State of Illinois, have invented a new and useful Improvement in Purifying Middlens, of which the following is a full, clear, and exact description, reference being had to the accompanying drawings making part of this specification, in which—

Figures 1 and 2 are end elevations. Fig. 3 is a longitudinal vertical section through the machine, showing the interior arrangement with the screen and supporting-links and the air-tube connecting with the fan, &c.

Our invention consists in an air-tube or trunk and a wind-spreader or distributor, combined with a middlens-purifier, so as to extend through a series of compartments under the screen, the tube being connected with the mouth of a blast-fan, and provided with adjustable wind-openings. By this means the force of the wind is regulated in each section and the current uniformly distributed, as we will now proceed to describe.

A is the frame of the machine, which should be constructed in a substantial manner. B is a screen covered with wire and bolting-cloth. C are links for suspending screen B. D is a fan for forcing a current of air into tube E, and from said tube through the openings H and K. E is a tube that connects with the mouth of the fan. H are openings on the side of air-tube. K are openings on the top of the air-tube. L are rods for moving the slides O for opening or closing the openings K. N is a triangular piece placed over the openings K, thereby preventing the middlens from falling into the tube; also, for spreading the current of wind as it escapes from the tube. The partitions P are placed across and under the bolt or screen B for regulating the force of the blasts or currents of air passing up through the screen, and allowing a heavier blast, if required, to pass through one part of the screen than the other.

The operation of our improved machine may be described as follows: The machine being

set in motion, the middlens to be purified are fed into the trough that is fastened onto the end of the screen, thence onto the bolt or screen B. The middlens as they enter the machine sift through rapidly, while the bran and brown specks are prevented from passing through the screen by the action of the wind from the blast-fan. The coarse bran moves off over the end of the screen, and the dust and fine particles are carried up and deposited in a dust-chamber. The fan being set in motion, the air is forced into the air-chamber, and passes into the compartment under the screen through the apertures or perforations of the air-tube.

The partitions P are so arranged that the air cannot pass from one section into the other, thereby securing in each section of the machine a sufficient current of air to remove the brown particles, according to their specific gravity, at the upper end. When the middlens are light a light blast is required, and in proportion to the coarseness of the middlens the openings are made in the air-tube. The air-tube E is arranged with slides in each section for opening or closing the openings K; also, a covering over the openings K for preventing the middlens falling into the air-tube. The covering or triangular piece N serves for spreading the wind, so that an equal current will pass through the bolting-cloth.

The rods L are fastened to the slides O for regulating the quantity of wind that passes out of openings K into each compartment. This action of the currents of air passing out from the air-tube on the sides and top is particularly valuable in its effect in having the force of the wind so regulated that each part of the screen will have a stronger or lighter current as the coarseness or fineness of the middlens require.

Having now described our improvements in middlens-purifiers, we wish to state we do not describe or claim those parts already patented by us in former patents; but

What we claim as new, and desire to secure by Letters Patent, is—

An air-tube or trunk, E, and a wind spreader or distributer, N, combined with a middlings-purifier, so as to extend through a series of compartments under the screen, the tube being connected with the mouth of the fan, and provided with adjustable wind-openings, substantially as described, for the purpose specified.

In testimony whereof we have hereunto set our hands this 5th day of July, A. D. 1873.

ANDREW HUNTER.

CHARLES EDWARD WHITMORE.
